UNITED STATES PATENT OFFICE

2,536,130

AIR HANDLING APPARATUS

Donald D. Herrman, Piqua, Ohio, assignor to
Hartzell Industries, Inc., Piqua, Ohio, a corpora-
tion of Ohio

Application May 21, 1946, Serial No. 671,360

3 Claims. (Cl. 230—120)

1

This invention relates in general to air han-
dling apparatus and particularly the means for
increasing the efficiency of operation of propeller
type fans.

An object of the invention is to provide an
annulus or shroud for a propeller type fan having
a predetermined contour for providing for a
smooth acceleration of air through the shroud
by the tip of the propeller operating within the
shroud.

Another object of the invention is to provide
an air-handling apparatus wherein a propeller
type fan is rotated within an annulus or shroud
with the tip of the propeller contained within the
shroud, and wherein the propeller is so positioned
within the shroud that the tip of the propeller
is sealed against return flow of air, said sealing
being occasioned by having the propeller of
slightly larger diameter than the discharge ori-
fice of the shroud by a selected and predeter-
mined amount.

Another object of the invention is to provide
an air-handling apparatus in accordance with
the foregoing object wherein the efficiency of
operation of the apparatus is increased through
controlling the width of the shroud relative to
the discharge orifice, and wherein the radius of
contour of the shroud is held within predeter-
mined limits relative to the diameter of the dis-
charge orifice.

Still another object of the invention is to pro-
vide an air-handling apparatus in accordance with
the foregoing objects wherein the shroud is
provided with a rounded edge on the upstream
side of the fan to provide for a gradual in-
crease of air velocity by the tip of the fan oper-
ating within the shroud.

Further objects and advantages will become
apparent from the drawings and the description.

In the drawings:

Figure 1 is a vertical cross-sectional view of
an air-handling apparatus constructed in ac-
cordance with this invention.

Figure 2 is a cross-sectional view taken through
the annulus or shroud to illustrate the contour
of the shroud and the position of a propeller
type fan therein in accordance with this inven-
tion.

Figure 3 is a cross-sectional view of an annulus
or shroud similar to Figure 2 but illustrating the
invention as applied to a shroud of larger dia-
meter than that of Figure 2.

Figure 4 is a cross-sectional view similar to 2
and 3 but illustrating the invention as applied
to an annulus of still larger diameter.

2

It is well known in the art of air handling de-
vices that propeller type fans rotating in open
air produce considerable air agitation at the tip
of the blades of the fan without producing any
substantial delivery of air under pressure. Vari-
ous types of shrouds or annulus have been tried
for the purpose of increasing the efficiency of
delivery from propeller type fans, particularly
by the blade tips, and for increasing the pres-
sure against which the fans will operate satis-
factorily for efficient delivery. The efficiency of
operation of a propeller type fan falls off rapidly
as the volume of air handled by the fan de-
creases and the fan works against increasing
static pressure.

It has therefore been the endeavor of persons
in this art to develop a propeller type fan and
shroud or annulus for the same that will main-
tain an efficient delivery of air over a greater
range of air deliveries, and will maintain ef-
ficient delivery of air against greater static pres-
sure without greatly increasing the horsepower
to operate the fan.

I have found in the development of propeller
type fans that the contour of the shroud or an-
nulus in which the fan operates plays an ex-
tremely vital part in determining the efficiency
of operation of a fan. Also, I have found that
the position of a propeller type fan within a
shroud, even of proper contour, also plays a vital
part in determining the efficiency of operation
of the fan.

Primarily, the width of the annulus or shroud
should be properly proportioned relative to the
discharge opening of the shroud, and the radius
of curvature of the shroud bears a definite rela-
tionship to the discharge orifice of the shroud.

If the shroud or annulus is properly contoured
in accordance with this invention, and a pro-
peller type fan is placed within the shroud for
operation therein with the tip of the blades of
the fan operating within the shroud and sub-
stantially sealed to the shroud by the close loca-
tion of the tips to the shroud with the proper
amount of blade overlap of the discharge orifice
of the shroud, the efficiency of operation of the
air-handling device will be greatly increased and
the device will be able to operate against greater
static pressures without losing its efficient air
delivery.

In this invention the shroud or annulus 10 is
circular in transverse cross-section. A propeller
type fan 11 is positioned within the shroud 10
and is adapted to be driven by any suitable source
of power. The blades 12 of the propeller 11 have

their tips 13 positioned in close proximity to the contoured wall of the annulus 10. It will be noted in Figure 1 that the tip diameter of the propeller 12 is greater than the discharge orifice 20 of the annulus 10, and is smaller than the inlet orifice 14. Also, it will be noted that the propeller tips are disposed within the annulus 10 for reasons hereinafter disclosed with regard to development of efficiency in the air handling device.

The annulus 10 is provided with a contoured or curved wall 15 that has the radius thereof generated from a plane substantially in the plane of the minimum diameter of the discharge orifice 20, which radius bears a relationship to the diameter of the discharge orifice 20 in the manner hereinafter disclosed.

The upstream edge of the wall 15, which forms the inlet orifice 14, is provided with a reversely curved position 16 of substantially aerofoil cross-section, thereby eliminating a sharp edge at the inlet orifice 14. The downstream side of the wall 15 is provided with a radially increasing opening which terminates in a radial flange 17 which thereby terminates the discharge orifice 20 with a small radiused corner 18.

As previously stated the contour of the shroud wall 15 and the position of the propeller therein is extremely important to obtaining maximum efficiency of operation of the propeller fan 11.

With reference to Figure 2 there is illustrated the special contour of the shroud wall 15 and the position of the fan blades 12 relative thereto for obtaining maximum efficiency of operation of the propeller fan.

The diameter of the discharge orifice 20 is indicated by the letter O and is the basic factor from which the other dimensions of the shroud 10 are established and to which the other dimensions of the shroud must bear a definite relationship within predetermined limits to obtain a shroud of satisfactory contour to obtain maximum efficiency from the propeller fan.

The width of the shroud 10 is indicated by the letter W. If the width of the shroud is too great there is undue friction to movement of air across the surface of the shroud, and adjacent thereto, which detracts from the maximum efficiency of air delivery by the tips of the propeller blades. On the other hand if the width of the shroud is too small there will be an insufficient surface area of the shroud for directing the air on the upstream side of the propeller blade toward the tip of the blade in a smoothly accelerating rate, and again the efficiency of delivery by the propeller tips will be decreased. I have therefore established that the width of the shroud bears a definite relationship to the diameter of the discharge orifice, and this relationship is that the width of the shroud shall be equal to the diameter of the orifice multiplied by .1, as a minimum dimension, and multiplied by .2 as a maximum dimension. Using the letters previously referred to the equation would be $W=O \times .1$ to .2. In other words the width of the shroud shall be from 10 to 20 per cent of the diameter of the discharge orifice.

I have also found that to give the maximum efficiency to air delivery by the tips of a propeller blade that it is essential that the shroud wall 15 be arranged upon a curve, and that the curvature of this wall 15, to obtain maximum efficiency of air delivery by the blade tips, bears a definite relationship to the discharge orifice 20 of the shroud. In Figure 2 the radius of curvature of

wall 15 is represented by the letter R, and this radius has its point of origin substantially in the plane of minimum diameter of the discharge orifice 20.

5 In Figure 2 it will be noted that the minimum diameter of the discharge orifice 20 is upstream from the discharge face 20A. The plane in which the radius R has its origin is this plane of minimum diameter of the discharge orifice 20. Also, 10 the point of origin of the radius R in the plane of minimum diameter of the orifice O is radially outside of the minimum diameter of the orifice by a dimension equal to the radius R.

The radius R of the curvature of the wall 15 15 of the shroud has been established to have a definite relationship to the orifice diameter O multiplied by .1 to .2 as a maximum radius. Again using the letters referred to previously the equation would be $R=O \times .1$ to .2.

20 The inlet opening 14 of the shroud 10 is provided with a rounded nose 15 as previously referred to, which is substantially in the form of a leading edge of an aerofoil to thereby cause the air entering the inlet on the upstream side of the shroud 10, to enter the shroud without shock and at a smoothly increasing velocity.

25 The downstream side of the shroud 10 terminates in the radius corner 18 to avoid the development of air agitation and eddy currents at this point.

30 It has also been stated that the position of the propeller within the shroud 10 is of extreme importance, and that the diameter of the propeller, represented by the letter T in Figure 2 bears a definite relationship to the orifice diameter O. It is essential that the tip diameter of the propeller, that is the disc swept out by the propeller blades during rotation, be greater than the discharge diameter O of the discharge orifice 20 35 and shall be less than the inlet diameter of the shroud 10. I have determined a definite relationship between the tip diameter T of the propeller 11 and the diameter O of the orifice 20 which obtains the maximum efficiency of air delivery between blade tips of the propeller.

40 If the tip diameter of the propeller is too small, even though larger than the diameter O of the discharge orifice 20, an effective seal is not provided between the propeller and the wall 15 of the shroud 10 to prevent air currents reversing within the shroud and producing air disturbance at the propeller tip which reduces the efficiency at the propeller tip in handling of air delivered through the shroud. Also, if the tip diameter of the propeller is greater than the diameter O of the discharge orifice 20 beyond a predetermined limit the maximum efficiency of air handling by the blade tips falls off rapidly. At all times, and within the limits of tip diameters established by this invention, I have found that the propeller tips must be positioned within the shroud 10 and in extremely close proximity to the wall 15.

45 I have found that the relationship between the tip diameter T of the propeller and the diameter O of the discharge orifice 20 shall be equal to the diameter O of the discharge orifice multiplied by 1.01 as a minimum tip diameter and shall be equal to the diameter O multiplied by 1.04 as a maximum diameter. In other words the diameter of the propeller, that is, the disc swept out by the blades in rotation thereof, relative to the diameter of the discharge orifice shall be greater by an amount of from one per cent to four per cent. Using the letters as previously referred

to, we find the equation to be $T=O \times 1.01$ to 1.04.

In Figure 2 there is shown in full lines the position of the propeller 11 relative to the shroud 16 with the tip diameter T of the propeller at the minimum diameter thereof greater than the diameter O of the orifice 20. The position of the propeller 11 relative to the shroud wall 15 with the tip diameter T at its maximum diameter relative to the diameter O of the orifice 20 is illustrated in dotted lines.

In Figure 1 there is illustrated the air flow through the tip of the propeller obtained by the use of this invention. The contoured inlet throat on the upstream side of the propeller provides for an area of relatively low pressure around the periphery thereof causing the air to greatly increase in velocity in its movement to the tip of the propeller and because of the curved inlet throat and aerofoil section on the nose of the inlet throat, the air moves toward the propeller tip, without shock, and with gradual increased velocity. The air handled by the propeller tips is completely delivered to the downstream side of the propeller because the propeller tips, working in close proximity to the wall 15, effectively seal against reverse movement of air within the shroud.

An air handling device constructed in accordance with this invention is capable of delivering substantially increased quantities of air against relatively high static pressures. Also, the total efficiency of the fan is maintained over a longer period on the fan curve, that is, the efficiency is maintained at a high level with greater quantities of air delivered by the fan without any substantial increase in the horse-power required to obtain the higher air deliveries, and without sacrifice of efficiency when working against higher static pressures. Thus the static efficiency of the fan also increases. As for example, an apparatus constructed in accordance with the invention has been tested to deliver 5,000 C. F. M. at a fan efficiency of seventy-two and one half per cent with use of .45 B. H. P.

In Figure 2 the contour of the shroud wall 15 and the position of the propeller fan therein has been based upon an orifice diameter O of twenty-two inches. In Figure 3 there is illustrated the relationship between the members heretofore related to as based upon an orifice diameter O of thirty-six inches, and in Figure 4 the orifice diameter O, is forty-eight inches. In each instance the shroud contour has been formulated according to the relationships heretofore set forth at the lower limits.

While the apparatus shown and described herein constitutes a preferred form of the invention, it should be understood that the apparatus is capable of alteration without departing from the spirit of the invention and that all modifications that fall within the scope of the appended claims are intended to be included herein.

Having thus fully described my invention, what I claim as new and desire to secure by Letters Patent is:

1. An air handling apparatus comprising, an

annulus having a discharge opening of less diameter than the inlet opening thereof and having an arcuate inner peripheral wall extending from the inlet opening to the outlet opening, said arcuate wall having a radius of between ten per cent and twenty per cent of the minimum diameter of the discharge opening and generated from a radial plane substantially coincident with the minimum diameter of said discharge opening, and terminating in a substantially aerofoil contour at the leading inlet edge thereof, and a propeller fan positioned in said annulus with the blade tips thereof in close proximity to the inner peripheral surface of said annulus and having a 15 diametral overlap of the discharge opening by the disc swept out by the rotation of the blades of between one per cent and four per cent of the diameter of the discharge opening.

2. An air handling apparatus comprising, an annulus having a discharge opening of less diameter than the inlet opening thereof and having an arcuate inner peripheral wall extending from the inlet opening to the outlet opening, said arcuate wall having a radius of between ten per cent and twenty per cent of the minimum diameter of the discharge opening and generated from a radial plane substantially coincident with the minimum diameter of said discharge opening, and a propeller fan positioned in said annulus 25 with the blade tips thereof in close proximity to the inner peripheral surface of said annulus and having a diametral overlap of the discharge opening by the disc swept out by the rotation of the blades of between one per cent and four per cent of the diameter of the discharge opening.

3. An air handling apparatus comprising, an annulus having a discharge opening of less diameter than the inlet opening thereof and having an arcuate inner peripheral wall extending from the inlet opening to the outlet opening, said annulus having a width of between ten per cent and twenty per cent of the minimum diameter of the outlet opening, said arcuate wall having a radius of between ten per cent and twenty per cent of the minimum diameter of the discharge opening and generated from a radial plane substantially coincident with the minimum diameter of said discharge opening, and a propeller fan positioned in said annulus with the blade tips thereof in close proximity to the inner peripheral surface of said annulus and having a diametral overlap of the discharge opening by the disc swept out by the rotation of the blades of between one per cent and four per cent of the diameter of the discharge opening.
